Inventor,

Hiram Kimball

UNITED STATES PATENT OFFICE.

HIRAM KIMBALL, OF PORT HURON, MICHIGAN.

RAIL-JOINT.

SPECIFICATION forming part of Letters Patent No. 249,184, dated November 8, 1881.

Application filed March 5, 1881. (No model.)

To all whom it may concern:

Be it known that I, HIRAM KIMBALL, a citizen of the United States, residing at Port Huron, in the county of St. Clair and State of Michigan, have invented a new and useful 5 Rail-Joint for Railroads, of which the following is a specification.

My invention relates to improvements in what are commonly known as "suspension joints," in which the ends of the rails are made to meet between two ties instead of on a tie; and the objects of my improvements are: first, to so connect and support the ends of the rails as to give the track at the joints as nearly as 10 possible the qualities of a continuous rail; second, to furnish a splice for the joint of such form that the head of the rail may be given the form that will wear the longest regardless of bearings for fish-plates; third, to give the 15 bottom of the rail ends independent support from bearings on the ties instead of supporting the end of one rail by clamping it to the other, and at the same time to give an increased area of bearings on the ties at the joints without placing metal between rails and ties, or 20 sinking the ties to allow placing supports under the rails or perforating the rails for bolts; fourth, to make such supports to the ends of the rails adjustable, so that any wear on the 25 bearings may be taken up and the joint given the desired degree of firmness; fifth, to obtain the foregoing advantages without the use of bolts, nuts, or screws. I attain these objects by the means illustrated in the accompanying drawings, in which—

Figure 1 is a vertical cross-section at the middle of the joint; Fig. 2, a side view, and Fig. 3 a top view, of the joint with the head of the rails cut off.

Similar letters refer to the same parts throughout all the views.

The ends of the rails A A are supported on the bottom by a chair or splice, B B C D, which rests on the ties T T by bearings on either side of but not under the rails, and also bears on the tops of the flanges of the rails over the ties by the lips b b b, and between the ties extends down and under the ends of the rails.

I prefer to make the chair in parts, substantially as shown, as being most conveniently made and applied. The two parts B B may be bolted together or held, as shown in the drawings, by the clamp D. The key C serves to adjust the tension of the joint and to take 55 up the wear.

It is obvious that the chair may be made in one piece instead of in parts, as shown, in which case it would have to be applied by sliding on the end of the rail. It is also obvious that the chair may rest entirely on the bearings on the ties, or entirely on the bearings on the flanges of the rail, and still retain many of the advantages of my invention.

I am aware of devices in which parts of the rail have been cut away and the chair made to fill up the space removed, and having parts extending under the bottom of the rail. My object is to effect a firm joint without interfering with or modifying the joint at the tread.

I am also aware that the rail's ends have been supported on the bottom by extensions of plates or splices bolted to the web of the rail, and I do not claim, broadly, the support of the joint by a chair extending under the end of the rail, except in the manner substantially as described.

What I do claim, and desire to secure by Letters Patent, is the following:

1. A rail-joint chair or splice in one or more pieces, resting on bearings on the ties on the sides of but not under the rails, or on bearings on the flanges of the rails over the ties, or on both, and between the ties extending down and under the ends of the rails, the whole being arranged below the tread of the rails, substantially as and for the purpose set forth.

2. In a rail-joint chair or splice, the bars B B, bearing on the ties on the sides of but not under the rails, or on the flanges of the rails over the ties, or on both, and between the ties extending down so as to carry plates crossing under and supporting the ends of the rails, substantially as described.

3. In combination with the bars B B, the clamp-plate D, crossing under the rails and holding the bars B B in position, substantially as described.

4. In combination with the bars B B, the key C, crossing under the rails, substantially as and for the purpose set forth.

5. A rail-joint chair composed of the bars B B, clamp D, and key C, substantially as described.

HIRAM KIMBALL.
